US00D469790S

(12) **United States Design Patent** (10) Patent No.: **US D469,790 S**
Vuorio (45) Date of Patent: ** Feb. 4, 2003

(54) **NOZZLE**

(75) Inventor: **Taisto Vuorio**, Espoo (FI)

(73) Assignee: **OY Trial AB**, Lohja As. (FI)

(**) Term: **14 Years**

(21) Appl. No.: **29/150,268**

(22) Filed: **Nov. 19, 2001**

(30) **Foreign Application Priority Data**

(57) **CLAIM**

The ornamental design for the nozzle, as shown and described.

DESCRIPTION

The claimed nozzle is used for cutting the paper web of a paper machine.

FIG. 1 is a side view of a nozzle showing my new design. The other side is symmetrical.

FIG. 2 is a bottom view of a nozzle shown in FIG. 1.

FIG. 3 is a side view of a nozzle showing an alternate embodiment of my new design. The other side is symmetrical.

FIG. 4 is a bottom view of the nozzle shown in FIG. 3.

FIG. 5 shows a side view of a nozzle showing an alternate embodiment of my new design. The other side is symmetrical; and,

FIG. 6 is a bottom view of the nozzle shown in FIG. 5.
